UNITED STATES PATENT OFFICE

167,643

FELT HAT BODY OR SIMILAR ARTICLE

John D. Mohn, Robesonia, Pa., assignor to Mohn Brothers Company, Incorporated, Reading, Pa., a corporation of Pennsylvania

Application December 21, 1951, Serial No. 17,794

Term of patent 7 years

(Cl. D3—13)

To all whom it may concern:

Be it known that I, John D. Mohn, a citizen of the United States of America, residing at Robesonia in the county of Berks and Commonwealth of Pennsylvania, have invented a new, original, and ornamental Design for a Felt Hat Body or Similar Article, of which the following is a specification, reference being had to the accompanying drawing, forming part thereof, wherein:

Fig. 1 is a side view of a felt hat body, showing my new design, and

Fig. 2 is a top view thereof.

The dominant feature of my new design resides in the external surface of the hat body having a net-like effect in contrasting colors presenting undulating rows of circles as shown.

I claim:

The ornamental design for a felt hat body or similar article, substantially as shown and described.

JOHN D. MOHN.
